UNITED STATES PATENT OFFICE.

PATRICK MULLOY AND HENRY FIRMINHAC, OF MERCER, WISCONSIN.

SPARK-EXTINGUISHER AND SMOKE-CONSUMER.

1,104,822.

Specification of Letters Patent.

Patented July 28, 1914.

Application filed November 9, 1912. Serial No. 730,451.

To all whom it may concern:

Be it known that we, PATRICK MULLOY and HENRY FIRMINHAC, citizens of the United States, residing at Mercer, in the 5 county of Iron, State of Wisconsin, have invented a new and useful Spark-Extinguisher and Smoke-Consumer, of which the following is a specification.

Our invention relates to an attachment 10 for locomotive smoke stacks which will effectively prevent sparks being blown from the stack and which will consume in a large degree the smoke issuing therefrom.

One of the objects of our invention is to 15 provide an apparatus of the class indicated in which the amount of water used to extinguish the sparks and consume the smoke will be dependent upon the locomotive throttle's position.

20 With the foregoing and other objects in view which will appear as the description proceeds, the invention resides in the combination and arrangement of parts and in the details of construction hereinafter 25 described and claimed, it being understood that changes in the precise embodiment of the invention herein disclosed, can be made within the scope of what is claimed, without departing from the spirit of the invention.

30 In the drawings accompanying this specification and forming a part thereof,—Figure 1 is a view in elevation with parts broken away showing a portion of a locomotive upon which is mounted our improved spark 35 extinguisher and smoke consumer. Fig. 2 is a detail plan view of the spraying ring, and Fig. 3 is a cross sectional view on the line A—A of Fig. 2. Fig. 4 is a view illustrating the manner in which the locomotive 40 throttle simultaneously controls the movement of the locomotive and the supply of the spray.

Referring to the drawings in which similar reference numerals designate correspond- 45 ing parts throughout the several views, 10 represents a locomotive boiler of the usual type and construction and is provided at its forward end with the smoke stack 11, at the upper end of which is fastened the spraying

50 ring 12, which ring is connected to the boiler 10 by means of the pipe 13. This pipe 13 enters the boiler at a point 20 which is below the normal water level in the boiler.

The spraying ring 12 is formed of a pipe 55 bent to conform with the inner periphery of the smoke stack, and is formed from metal

especially designed to withstand such conditions as are met with at the upper inner edge of a locomotive smoke stack. Apertures 14 are formed in the walls of this ring 60 and extend obliquely to the plane of the ring so that the water as sprayed therefrom will tend to move in a central and downward direction. A T 21 is fastened to the two ends of the said ring and one arm thereof 65 extends through the side walls of the locomotive stack and communicates with the pipe 13.

Connected to the boiler is a supply valve 16, a controlling valve 17 being positioned 70 a slight distance above the valve 16 and is connected to and actuated by a lever 18. The lever 18 is connected by a link 23 to a bell crank lever which latter is arranged in the path of movement of and actuated by 75 the locomotive throttle valve 22. In this connection it is to be noted that as shown in Fig. 4, as the throttle valve lever 22 is moved to open the throttle valve 24, the valve 17 will also be opened. A third valve 80 19 is provided to regulate the supply of water to the spraying ring and is designed to be set and when once set is designed to remain always in that position. The supply valve 16 is designed to be closed at the end 85 of each run of the engine.

It is known that the number of sparks and the amount of smoke issuing from the stack will depend upon the throttle position as the steam from the cylinder is exhausted 90 into the stack. Therefore by connecting the throttle with the controlling valve 17, the greater the amount of smoke and number of sparks issuing from the stack, the greater the amount of water that will be 95 supplied to the spraying ring.

A shield 15 is secured to the upper end of the locomotive stack and is frusto-conical in shape and this shield insures that no live 100 sparks will be allowed to issue from the smoke stack. This shield necessitates that the smoke and sparks issue from the center of the stack and it is at the center of the stack that the spraying ring most effectively sprays.

From the foregoing it will be seen that we have designed a most efficient and durable spark extinguisher and smoke consumer.

What we claim to be new and original 110 with us is:—

1. The combination with a boiler, a smoke

stack, and a throttle, of a spraying ring attached to the said smoke stack, a pipe communicating therewith and with the boiler below the normal water level thereof, and 5 means actuated by the said throttle controlling the amount of water supplied to said spraying ring.

2. In an apparatus of the class described, the combination of a smoke stack, a boiler, a 10 throttle, a spraying ring secured to the inner surface of said smoke stack, a pipe communicating therewith and with the boiler below the normal level thereof, a supply valve in said pipe, a regulating valve in 15 said pipe, and a controlling valve in said pipe secured to and actuated by said throttle.

3. In apparatus of the class described, the combination with a locomotive stack, a locomotive boiler, and a locomotive throttle, 20 of a ring carried by the upper inner edge of the said stack and provided with a plurality of openings extending therethrough, a pipe communicating with said ring and 25 with the locomotive boiler below the water line of the latter, a supply valve located in

said pipe adjacent the boiler connection thereof, a controlling valve located beyond the said supply valve and actuated by and in conjunction with the locomotive throttle, 30 and a regulating valve located beyond said controlling valve.

4. In apparatus of the class described, the combination with a locomotive boiler, a smoke stack, and a throttle, of a frusto-conical shield secured to said smoke stack at its upper end, a spraying ring disposed within and housed by the said frusto-conical shield, a pipe communicating with said ring and with the locomotive boiler below the water 40 line thereof, supply, controlling and regulating valves located in said pipe, and the said controlling valve actuated by and in conjunction with the locomotive throttle.

In testimony that we claim the foregoing 45 as our own, we have hereto affixed our signatures in the presence of two witnesses.

PATRICK MULLOY.
HENRY FIRMINHAC.
